DISPLAY FORM

Lillian L. Greneker, New York, N. Y.

Application June 2, 1938, Serial No. 211,401

9 Claims. (Cl. 223—68)

My present invention relates generally to display forms, and has particular reference to a device which simulates the human body.

It is a general object of the invention to provide an improved display form, intended primarily for use in store windows and the like, to support and display women's garments.

One of the main objects of the invention is to provide a display form in which the medial or 10 waist portion is flexible so as to permit adjustments of the simulated human figure into various adjusted positions.

A more particular object is to provide an adjustable or flexible waist portion which is so constructed and arranged that accurate life-like 15 contours of the waist portion, the abdomen, the small of the back and the hips are always maintained.

A characterizing feature of the present construction lies in the employment of a tubular element comprising hingedly connected superposed 20 rings whose shapes conform substantially to the corresponding superposed ribs of the human body. The rings have flat outer surfaces which 25 serve conjointly to define a substantially smooth surface conforming quite accurately to the contours of the waist and hip portions of the human body. The device is therefore admirably adapted to support a tailored garment, even a 30 relatively sheer snug-fitting gown or the like, with maximum effectiveness.

The rings are articulated by connecting portions each of which projects inwardly, defining an annular groove or channel of substantially V-shaped cross-section. In this way, adjustments 35 of the rings relative to one another are accompanied by life-like variations in the contours of the waist, the hips and adjacent portions of the body that is simulated.

40 It is a particular feature of my invention to construct the rings so that the side portions are downwardly curved in the form of inverted arches while the front portions are upwardly arched, and so that the rear portions of the lower rings 45 are of undulating shape; these special configurations serving to enhance the simulation of hips, and adjacent regions.

In a preferred construction, the tubular element is composed of a single piece of form-retaining material such as rubber or its equivalents. Preferably, the tubular element is formed of two spaced walls, the inner one serving as a reinforcement and being spaced from the outer 50 wall except at the upper and lower ends of the

tubular element, where it unites with the outer wall.

The display form consists essentially of an upper relatively rigid chest portion, and a lower relatively rigid pelvic portion, the flexible waist portion being arranged between, with the smooth contours of the waist portion merging with, and thereby forming continuations of, the smooth contours of the upper and lower rigid portions of the display form.

In order to maintain the two rigid portions in predetermined spaced relation, while nevertheless permitting limited relative adjustments, it is a feature of my invention to provide a flexible post which is arranged on the interior of the 15 tubular waist portion, and which extends in a substantial vertical direction between the rigid pelvic portion and the rigid chest portion. The tubular post is subjected, in use, to relatively severe and repeated bendings and adjustments, and 20 to withstand this treatment, I purposely construct the tubular post of two nested tubes of spirally-wound material, the tubes spiralling in opposite directions.

I achieve the foregoing objects and such other 25 objects as may hereinafter appear or be pointed out, in the manner illustratively exemplified in the accompanying drawings in which—

Figure 1 is an elevational front view of the central portion of a display form constructed in accordance with my present invention.

Figure 2 is a side view on a somewhat enlarged scale.

Figure 3 is a rear view, on the same scale as Figure 2.

Figure 4 is a front view on the same scale as Figure 2, showing the waist portion in an adjusted position.

Figure 5 is a greatly enlarged cross-sectional view taken substantially along the line 5—5 of Figure 2.

Figure 6 is a cross-sectional view taken substantially along the line 6—6 of Figure 1.

Figure 7 is an enlarged fragmentary cross-sectional view through the lower portion of the flexible waist element, and

Figure 8 is a view similar to Figure 7 showing a modification.

Referring to Figures 1 and 5, the chest portion 50 is relatively rigid by virtue of the arrangement, at its base, of the rigid block 11 which may be of wood or other suitable material. This block is provided on its lower surface with a recess 12 adapted to accommodate the upper end of the flexible post hereinafter to be described. Simi- 55

larly, the pelvic portion 13 is relatively rigid by virtue of the arrangement at its top of the block 14, of wood or the like, provided with the recess 15 adapted to accommodate the lower end of the 5 flexible post.

The outer surfaces of the chest and pelvic portions 10 and 13 may be constructed in any desired or conventional manner, and merely for 10 illustrative purposes, I have shown surface coverings 16 which may be of any suitable material. These details form no part of the present invention, and need not therefore be described. Similarly, the details of the head, the arms, the 15 legs, etc., are omitted from the drawings and will 10 not be referred to herein, it being understood that any desired construction, assembly or articulation, may be resorted to.

The important point is that the upper and lower portions 10 and 13 have external smooth 20 contours simulating the corresponding portions of the human body, these contours merging with, and being completed by, the external contours of the flexible waist portion.

This waist portion is in the form of a tubular 25 element designated generally by the reference numeral 17 and comprising a series of superposed rings 18. These rings have flat outer surfaces, as will be clearly observed from the drawings, and the shapes of the rings are of such a character 30 that they conform substantially to the corresponding superposed ribs of the human body, whereby the flattened outer surfaces of the rings conjointly define a substantially smooth surface, conforming quite accurately to the contours of 35 the corresponding portions of the human body.

I draw particular attention to the fact that the side portions of the rings, designated by the reference numeral 19 in Figure 2, are downwardly curved in the form of inverted arches at the middle 40 of the sides, while the front portions of the rings, observed most clearly in Figures 1 and 4, are upwardly arched. This enhances the simulation of hips and abdomen, especially during adjustments of the rings relative to one another. It 45 will also be observed that the rear portions 20 of the lower rings, seen most clearly in Figure 3, are of undulating shape. This enhances the simulation of the concavity in the region of the small of the back. This concavity is further enhanced by bending the rings inward, as shown at 50 21 in Figure 6, adjacent to the lower portion of the waist element.

The rings are articulated or hinged by inwardly projecting portions 22 (see Figure 7) which are 55 substantially V-shaped in cross-section, thereby defining annular grooves. These V-shaped connecting portions permit relative adjustments of the rings so that the display form may be bent at the waist into various adjusted positions which 60 simulate corresponding bent postures of the human body. Merely by way of example, I have shown, in Figure 4, the manner in which the rings adjust themselves when the display form has the waist portion bent toward the right. It will be 65 observed that the ring portions at the right side of the "body" come into close proximity to one another, while the opposite ring portions, at the left side of the "body", become slightly more spaced. These adjustments are possible by virtue 70 of the fact that the V-shaped connecting portions 22 contract and expand, as will be clearly apparent from a comparison of the full-line showing of Figure 7 with the dot and dash representation of the corresponding parts.

75 The important thing to note is that life-like

contours are maintained during the adjustments, whereby the display of garments, even close-fitting dresses or gowns, is capable in an unusually attractive manner.

In the preferred embodiment the waist portion 5 is composed of a single element of form-retaining flexible material such as rubber, the rings 18 being thus integral portions, along with the connections 22, of a single piece. Preferably, this tubular element incorporates an inner wall 23 10 which is spaced from the outer wall and which is of undulating character with its peaks in alignment with the rings, and with its valleys aligned with the connecting portions 22. This inner wall serves as an efficient reinforcement for the 15 entire structure and merges with the outer wall at the upper and lower ends of the waist portion, these ends being secured to the rigid portions 10 and 13 by means of tacks 24, or nails or other fastening means. The inner wall 23 is preferably formed of the same integral piece of material as the outer wall, the entire structure being capable of being molded as a unit.

In Figure 8, I have illustrated a modification in 25 which the rings 25 are separate elements of relatively rigid material, and are hingedly articulated by means of outer and inner coverings 26 and 27. These coverings may be of cloth or other flexible fabric, and each ring is completely sandwiched between a strip 26 and a strip 27, stitches 30 28 serving to hold the ring in place. The two superposed ends of the coverings 26 and 27 are then secured by stitching 29 to the corresponding ends of the coverings for the adjacent ring. This provides the inwardly projecting connecting portions, of substantially V-shaped cross-section, 35 hereinbefore exemplified by the portions 22 of Figure 7.

The rings 25 of Figure 8 have the same shapes as the rings hereinbefore described, and the device functions in every respect exactly the same 40 as the preferred form.

The flexible post between the chest and pelvic portions consists of the nested inner and outer tubes 30 and 31 shown most clearly in Figure 5. 45 These tubes are suitably secured, as by welding, to metal plates 32 and 33 mounted in the recesses 13 and 15 respectively. Each tube consists of a spirally wound strip, preferably of metal, the strip having an S-shaped cross-section 50 whereby each convolution of the spiral interlocks with the adjacent convolution. A spirally wound tube of this character is well known per se and has heretofore been employed as a flexible support in a variety of arts, including display forms. 55 It is a particular feature of my invention, however, to wind the inner tube 30 in a direction opposite to that of the outer tube 31. One tube thus reinforces the other, and prevents either tube from becoming loosened, through wear and 60 tear, to a degree which would impair the efficient functioning of the device.

It will be understood that the flexible tube is form-retaining, i. e., it is adjustable into bent 65 positions, as shown in Figure 4, but it retains whatever limited curvature is imparted to it.

The uniquely efficient nature of the present display form is attributable, I believe, not only to the novel flexible waist portion, but also to the conjoint use of this flexible element with the 70 flexible supporting tube in its interior, because it is this cooperative action of the parts which so accurately simulates actual adjustments of the human body at the waist portion.

It will, therefore, be understood that changes 75

in the details, herein described and illustrated for the purpose of explaining the nature of my invention, may be made by those skilled in the art without departing from the spirit and scope 5 of the invention as expressed in the appended claims. It is, therefore, intended that these details be interpreted as illustrative, and not in a limiting sense.

Having thus described my invention, and illustrated its use, what I claim as new and desire to secure by Letters Patent is—

1. In a display form simulating the human body, a flexible waist portion composed of a tubular element comprising hingedly connected superposed rings of fixed predetermined sizes, said rings having flat outer surfaces conjointly defining a substantially smooth surface conforming to the contours of the waist and hip portions of the human body, and said rings being downwardly arched at the middle of the sides of the waist portion and being upwardly arched at the front thereof to enhance the simulation of hips and abdomen, whereby adjustments of the rings relative to one another are accompanied by life-like variations in said waist and hip contours.

2. A flexible waist portion as set forth in claim 1, the rear portions of the lower rings being of undulating shape to enhance the simulation of the concavity in the region of the small of the back.

3. A flexible waist portion as set forth in claim 1, the hinge connection between each two rings comprising an inwardly projecting portion of substantially V-shaped cross-section.

35 4. A flexible waist portion as set forth in claim 1, said tubular element comprising two spaced walls, the outer wall defining said rings and hinged connections, the inner wall serving as a reinforcement spaced from the outer wall, said 40 walls being united at the upper and lower ends of said tubular element.

45 5. In a display form simulating the human body, a rigid chest portion, a rigid pelvic portion, and a flexible waist portion between said rigid portions, said waist portion being a tubular element secured at the top to the chest portion and at the bottom to the pelvic portion, said element comprising hingedly connected superposed rings 50 of fixed predetermined sizes, said rings having flat outer surfaces conjointly defining a substantially smooth surface which merges with the surfaces of said chest and pelvic portions and conforms to the contours of the waist and hip portions of the human body, the side portions of the rings being downwardly curved and the front

portions being upwardly arched to enhance the simulation of hips and abdomen.

6. In a display form, the combination with the elements set forth in claim 5, of a flexible but form-retaining post arranged in the interior of 5 said tubular element and extending between said rigid portions to support the chest portion in predetermined spaced relation from the pelvic portion.

7. In a display form, the combination with the 10 elements set forth in claim 5, of a flexible but form-retaining post arranged in the interior of said tubular element and extending between said rigid portions to support the chest portion in predetermined spaced relation from the pelvic 15 portion, said post comprising nested tubes of spirally-wound material, said tubes spiraling in opposite directions.

8. In a display form simulating the human body, a flexible waist portion composed of a tubular element comprising hingedly connected superposed rings of fixed predetermined sizes, said rings having flat outer surfaces conjointly defining a substantially smooth surface conforming to the contours of the waist and hip portions 20 of the human body, the side portions of the rings being downwardly curved and the front portions being upwardly arched to enhance the simulation of hips and abdomen, whereby adjustments 25 of the rings relative to one another are accompanied by life-like variations in said waist and hip contours, the hinge connection between each two rings comprising an inwardly projecting portion of substantially V-shaped cross-section, said 30 rings and connecting portions being formed of a 35 single element of form-retaining rubber.

9. In a display form simulating the human body, a flexible waist portion composed of a tubular element comprising hingedly connected superposed rings of fixed predetermined sizes, 40 said rings having flat outer surfaces conjointly defining a substantially smooth surface conforming to the contours of the waist and hip portions of the human body, the side portions of the rings being downwardly curved and the front portions 45 being upwardly arched to enhance the simulation of hips and abdomen, whereby adjustments of the rings relative to one another are accompanied by life-like variations in said waist and hip contours, the hinge connection between each 50 two rings comprising an inwardly projecting portion of substantially V-shaped cross-section, said rings and connecting portions being formed of a single element of form-retaining flexible material.

55 LILLIAN L. GRENEKER.
